UNITED STATES PATENT OFFICE.

WILLIAM H. HOSCHKE, OF NEW YORK, N. Y.

DESIGN FOR A PHONOGRAPH-CASE.

No. 40,137.

Specification for Design.

Patented July 13, 1909.

Application filed May 22, 1909. Serial No. 497,810. Term of patent 7 years.

To all whom it may concern:

Be it known that I, WILLIAM H. HOSCHKE, a citizen of the United States of America, residing in New York, in the borough of Brooklyn, county of Kings, and State of New York, have invented a new, original, and ornamental Design for Phonograph-Cases, of which the following is a specification, reference being had to the accompanying drawing, forming part thereof.

The figure is a perspective view of a phonograph-case, showing my new design.

I claim:

The ornamental design for a phonograph-case, as shown.

WILLIAM H. HOSCHKE.
